WINCHESTER REPEATING ARMS COMPANY, OF NEW HAVEN, CONNECTICUT, A
CORPORATION OF CONNECTICUT.

HANDLAMP SWITCH.

1,419,729.

Specification of Letters Patent. Patented June 13, 1922.

Application filed January 8, 1920. Serial No. 350,145.

To all whom it may concern:

Be it known that I, GEORGE D. GALLAGHER, a citizen of the United States, residing at Washington, District of Columbia, have invented certain new and useful improvements 5 in Handlamp Switches (Case B); and I do hereby declare the following to be a full, clear, and exact description of the invention, such as will enable others skilled in the art 10 to which it appertains to make and use the same.

The present invention relates to portable lamps of a character comprising a battery and a small incandescent electric lamp with 15 a switch suitably positioned to control the flow of current from said battery through said lamp.

In devices of this general character, it is desirable that the operator be able to 20 flash the lamp, that is to say, light it momentarily as in signaling, or for such short periods of time as is convenient for the operator to hold his thumb on the switch mechanism. It is also desirable that the 25 contact device be so arranged as to give a permanent or continual lighting of the lamp without the need for continuing thumb pressure on the contact device. There is also a need for rendering the contact device in- 30 active to prevent inadvertent lighting of the lamp through accidental manipulation of the contact device, as when the hand lamp is carried about in a tool kit, or is being stored or transported with its battery in 35 place.

It is an object of the present invention to satisfy any and all of the foregoing requirements by a contact means of simple and economical construction, easy to manufacture and assemble, and reliable in its action.

Other objects and advantages are herein- 40 after pointed out and will be clear from the following detailed description, which is to be taken in conjunction with the accompany- 45 ing drawings, wherein—

Fig. 1 is a sectional elevation of a hand lamp embodying the present invention;

Fig. 2 is an enlarged plan of the switch or contact mechanism;

Fig. 3 is a section on the line 3—3 of Fig. 2;

Figs. 4 and 5 are corresponding sections with the switch button rotated from the position illustrated in Fig. 3;

Fig. 6 is a transverse section on the line 6—6 of Fig. 2; 55

Figs. 7 and 8 are details of the push button switch;

Figs. 9 and 10 are details of a rotary element of the switch; and

Fig. 11 is a section through the leaf spring 60 by which movement of the push button is controlled.

In the embodiment illustrated, a plurality of dry cells 1 are arranged end to end with the upper or carbon electrode 2 of the top-most cell making contact with the inner terminal of the lamp 3, and the naked or zinc bottom of the lowermost cell making electrical connection through the coil spring 4 with a metal cap 5 threaded to a collar 6. 65 positioned on the lower end of the casing 7. This casing may be of fiber or other material commonly used in hand lamps, and may be provided at its front end with a threaded collar 8 carrying a flanged ring 9 by 70 which the lens 10 and lamp reflector 11 are held in position. Preferably the edge of reflector 11 is spaced from collar 8 and ring 9 to make the hand lamp non-short-circuiting, but those and other details of the device may 75 be varied in many ways. 80

Connected with the outer terminal of the lamp 3, as through reflector 11, is a conductor 12, which may be in the form of a flat strip running along the inner wall of casing 85 7 and secured near its lower end by a rivet 13. The lower end of conductor 12 is preferably bent outward at right angles to form a contact element 14 which protrudes through an elongated slot in casing 7, as 90 shown in Figs. 3 to 5, inclusive. Positioned over this slot is a sheet metal housing 15 with an escutcheon plate 16 by which the housing may be suitably riveted to casing 7. The central portion of this housing is of rectangular outline, as shown in Fig. 2, and is slotted along each side to receive a rotatable disc 17 wherein the push button 18 of the contact device is mounted and by which it may be rotated. The push button is pref- 95 erably provided with four recesses 19 cut in the side walls thereof and engaging with four projections 20 on the inner edge of the rotatable disc 17. The push button is thus free to move in and out but cannot rotate 100 axially except when disc 17 also rotates. 105

The push button carries at its inner edge a flange of irregular shape, as shown in Fig. 8, with portions of two of its sectors 21 cut away, and with the two remaining sectors 5 22 left intact.

Movements of the push button 18 are controlled by a bent leaf spring 23 (Fig. 11), the lower end of which is fastened to the housing by a rivet 24, and the upper, broad, 10 flat end of which fits against the under circular face of push button 18 in which are a pair of intersecting grooves 25 and 26 (Fig. 8) in which the outer end of spring 23 is received and by which accidental rotation 15 of the push button is avoided. When the push button is rotated, as hereinafter explained, the spring snaps in and out of these intersecting grooves 25 and 26.

With the several parts in the positions 20 shown in Fig. 3, thumb pressure on push button 18 will bring the flat segments 21 and 22 of its flange into engagement with the upturned end 14 of the conductor from the lamp and will thereby complete the circuit 25 from the battery through the lamp, it being understood that spring 23, housing 15 and escutcheon 16 are electrically connected with the bottom of the dry cells as through a flat strip 27 (Fig. 1) leading to the metal fittings of the casing 7. It is in this way that 30 the lamp is flashed, i. e., is lighted for such periods of time as it is convenient for the operator to hold his thumb on the push button. But if a permanent lighting of the 35 lamp is desired, the operator slides his thumb along the edge of disc 17 and thereby rotates the disc and with it the push button to bring the disc itself into electrical connection with the bent and yielding end 14 of conductor 13 over which the disc rides with a wiping 40 action and so completes the connection without the need for pressure on the push button. Details of the rotary disc 17 are best 45 shown in Figs 9 and 10, from which it will be seen that the cut away portions 28 and 29 of the lower face of the disc are separated by tongues 30 and 31, either one of which when 50 engaged with contact 14 will complete the circuit from the battery through the lamp. 55 With the rotary disc in the position shown in Fig. 3, neither of these tongues 30 or 31 is in contact with conductor 14, and inward movement of the push button is necessary to complete the circuit. In Fig. 4 the rotary disc has been turned 90° from the position 60 occupied in Fig. 3, and thus has become effective to cause permanent lighting of the lamp.

But if lighting of the lamp is to be avoided, as when the hand lamp is being shipped 65 through the mails, or is being carried as baggage or in the tool kit of an automobile, the rotary disc 17, and with it the push button 18, can be rotated still further until they assume the position shown in Fig. 5 with

the cut away portion of rotary disc 17 over contact 14, and with the cut away portion of the push button flange over conductor 14. Thumb pressure on the push button in this axial position will not bring any part of the 70 button into contact with conductor 14 to light the lamp. Rotation of the push button and its disc 17, though entirely feasible from an operating standpoint, is not likely to occur accidentally because of the seating 75 of spring 23 in one or the other of the recesses 25 and 26 formed in the inner circular face of the push button.

I am aware that details of the switch mechanism may be varied within the scope 80 of the appended claims, and it will be apparent that the shape, size and materials of various parts of the hand lamp structure with which this contact device is used may be altered in many ways without departing 85 from the spirit of my invention as defined by the appended claims.

I claim:—

1. Contact means for a battery hand lamp, comprising a push button and an opposed contact for flashing the lamp, and means engaged by said push button and rotatable therewith and into continuing engagement with said opposed contact when permanent lighting of the lamp is desired. 90

2. Contact means for a battery hand lamp, comprising a push button for flashing the lamp, and additional contact means engaged by said push button and rotatable on the axis of said push button into inactive position 100 when lighting of the lamp is to be avoided.

3. Contact means for a battery hand lamp, comprising a contact disc, a conductor opposite said disc, said disc having an unsymmetrical working face and being adapted 105 by rotation to assume two different positions, in one of which it closes the circuit through said opposed conductor, and in another of which it leaves the circuit open, and a push button having an unsymmetrical working 110 face and being rotatable with said disc into inactive position when lighting of the lamp is to be avoided, substantially as described.

4. Contact means for a battery hand lamp, a flanged push button and a disc 115 through which said push button passes and by which it may be rotated, said disc having a portion effective to light the lamp when continuous lighting is desired.

5. Contact means for a battery hand lamp, a housing, a disc rotatably carried 120 thereby, a push button passing through said disc and shaped for temporary engagement with an opposed conductor, said disc being shaped for permanent engagement with said 125 conductor when continuous lighting of the lamp is desired, and a spring for controlling the movement of said push button.

6. Contact means for a battery hand lamp, a housing having openings in its sides, 130

a disc mounted to rotate in said openings and having recesses in its inner edge, a push button having projections engaging said recesses and rotatable thereby, and a spring urging said push button outward, said push button having a flange of irregular shape permitting intermittent lighting of the lamp

when the push button is in one position and said disc having a tongue for closing the circuit to light the lamp when said push button is in another position.

5 In testimony whereof I affix my signature.

GEORGE D. GALLAGHER.

Certificate of Correction.

It is hereby certified that in Letters Patent No. 1,419,729, granted June 13, 1922, upon the application of George D. Gallagher, of Washington, District of Columbia, for an improvement in "Handlamp Switches," an error appears in the printed specification requiring correction as follows: Page 2, lines 115, 121, and 130, claims 4, 5, and 6, after the word "lamp" insert the word *comprising*; and that the said Letters Patent should be read with this correction therein that the same may conform to the record of the case in the Patent Office.

Signed and sealed this 11th day of July, A. D., 1922.

[**SEAL.**]

KARL FENNING,

Acting Commissioner of Patents.
